UNITED STATES PATENT OFFICE.

CHARLES HENRY CALHOUN, OF MILFORD, DELAWARE.

RAIL-FASTENER.

1,178,381.

Specification of Letters Patent.

Patented Apr. 4, 1916.

Application filed August 5, 1915. Serial No. 43,817.

To all whom it may concern:

Be it known that I, CHARLES H. CALHOUN, a citizen of the United States, residing at Milford, in the county of Kent and State of Delaware, have invented new and useful Improvements in Rail-Fasteners, of which the following is a specification.

The present invention relates to improvements in means for automatically securing 10 a rail upon a tie.

Another object of the invention is to provide a rail stay or anchor which is designed to prevent the longitudinal creeping of the rails and which comprises a pair of members 15 normally arranged at an angle with relation to each other but which are forced into locking position with both the rail and the tie by the weight of the rail when resting upon the said ends.

Another object of the invention is to provide a rail fastening means including a pair 20 of clamps or anchors designed to be forced into rail engaging position when the weight of the rails is interposed thereon, the tie upon which the anchors are disposed being provided with cushion members which receive and relieve the anchor members from the shock and jar incident to the weight of the rolling stock traveling thereover.

With the above and other objects in view, the improvement resides in the construction, combination and arrangement of parts set forth in the following specification and falling within the scope of the appended claims.

In the drawings: Figure 1 is a top plan view showing a portion of a railway rail arranged and secured upon a tie in accordance with the present invention, Fig. 2 is a side elevation of the same, a portion of the tie 35 being shown in section, Fig. 3 is a transverse sectional view illustrating the arrangement of the rail securing members before the rail is arranged thereon, a portion of said rail being shown in section elevated above the anchoring members and in a position to be laid thereon. Fig. 4 is a similar sectional view on the line 4—4 of Fig. 2, Fig. 5 is a plan view of the tie with the rail removed therefrom, Fig. 6 is a perspective view of 40 one of the anchor or rail securing members, and Fig. 7 is a transverse sectional view

taken through a wooden tie provided with my improvement and illustrating rails secured thereon.

Referring now to the drawings in detail, 55 the numeral 1 designates a rail of the ordinary construction, and 2 the tie upon which the rail rests. In the preferred form of my improvement the tie may be constructed of any desired material and is, adjacent its 60 ends, provided with transverse depressions 3 forming passages for the reception of the base flanges of the rails as well as for other purposes which will presently be described. The passages 3 are wider than is the width 65 of the base flange of the rail 1, and the transverse walls of each of said passages is preferably beveled or inclined in opposite directions, forming what may be termed overlying ledges and which are indicated by the 70 numerals 4. The walls or ledges 4 are of substantially ogee formation, and the lower or horizontal walls of the passages 3, adjacent the side walls 4 thereof are beveled toward the said side walls, as indicated by the 75 numeral 4', so that the lower portion of the said side walls are disposed below the plane of the horizontal wall of the said passage 3.

The numerals 6 designate two similar rail stay members or clamps. Each of the members 6 includes a substantially rectangular body 7, the lower wall of which being straight, but the upper wall is inclined from one of its ends toward its opposite end, as indicated by the numeral 8, and what I will 80 term the inner portion of the wall 8 being beveled downwardly at its end toward the bottom wall 9 of the body 7, as indicated by the numeral 10. The widened end of the body 7 upon its upper or inclined wall 8 is 85 formed with an integral rail engaging hook or clamping member 11, the same conforming to the cross sectional shape of the longitudinal edge of the base flange of the rail, while the body, beyond the said hook 11, is 90 formed with an extension 12, the outer wall of which is rounded from the outer wall of the hook 11 to the lower wall 9 of the body 7 providing a sharpened entering point 13. This portion 13 is adapted to be received 95 upon the beveled or inclined ends 4' of the horizontally straight wall of the passage 3,

and when the members 6 are so arranged it will be noted that the portions 10-10 thereof are maintained approximately horizontally straight with relation to the tie and 5 also with relation to the base flange of the rail 1. The rail is lifted above the portions 10, as shown in Fig. 3 of the drawings, and the weight of the rail swings the members 6 upon their entering ends 13, the said entering ends serving as fulcrums for the members.

In order that the rails may not constantly bear upon the members 6, I have found it desirable, when metallic ties are employed, 15 to provide the same with longitudinally extending depressions 14 which intersect the passages 3, the said depressions being disposed to the opposite sides of the rail engaging members 6, and I also arrange between each of said depressions 14 a cushion block 15 upon which the base flanges of the rails rest. Also I have found it desirable to channel the tie centrally between the depressions 14-14, as indicated by the numeral 16, 20 the said channel being arranged in the central portion of the passage 3 and being disposed adjacent the ends of the members 6-6. This channel 16 is adapted to permit of the insertion of a pinch bar or the like beneath 25 the members 6-6 to swing the same upon their entering or fulcrum points 13 to elevate the beveled ends 10 thereof and to permit of the separation of the rail from the said members as well as the removal of the 30 said members from the passages 3.

When the device is employed in connection with a wooden tie, as illustrated in Fig. 7, the entering points 13 penetrate the side walls 17 of the channels 18 provided to receive the members 6'.

From the above description, taken in connection with the accompanying drawings, the simplicity of the device, as well as the advantages thereof will, it is thought, be 45 perfectly apparent to those skilled in the art to which such invention appertains without further detailed description.

Having thus described the invention, what I claim is:

50 1. In combination, a tie having a transverse rail receiving passage, a pair of oppositely disposed rail clamping members adapted to be arranged within the passage, said member including body portions having their upper faces inclined from one of their ends to their opposite ends and having the said upper faces formed with rail engaging hooks, beveled portions disposed beyond the hooks and contacting with the side 55 walls of the passage and adapted to be forced to within the said side walls when the weight of the rail is deposited upon the said members.

60 2. In an automatic rail fastener, the com-

bination with a tie having a transverse channel, the side walls of which being of an ogee formation, two similar rail engaging members each including a substantially rectangular body portion, the upper wall of which being inclined from one of its ends to its 70 opposite end and the inner walls of each of said members being beveled and the inclined wall to the lower straight wall thereof and the outer enlarged ends of said members being rounded and being received one with- 75 in the respective ogee walls of the passage, and the members being provided with hooks adapted, when the said members are forced to within the passage by the weight of the rail thereon to engage with the longitudinal 80 edges of said rail.

3. In an automatic rail fastener, the combination with a tie having a transverse rail receiving passage, the side walls of the passage being beveled inwardly and the horizontal lower wall of said passage being beveled at the ends thereof toward the inclined sides, metal clamps arranged side by side within the passage and having their opposite ends enlarged and rounded to engage 90 within the side walls provided by the passage, the lower portions of the bodies of each of the clamp members being horizontally straight, the upper walls being rounded to their inner walls and their inner walls being beveled to their ends and adapted to be arranged horizontally straight when the said members rest upon the inclined ends of the horizontal lower wall of the passage, and the said members being formed with hooks 95 which are adapted to engage with the longitudinal edges of the rail when the weight of the rail is imposed thereon and the bodies of the members are swung to within the 100 passage.

4. In an automatic rail fastener, the combination with a tie having a transverse rail receiving passage, the side walls of the passage being beveled inwardly and the horizontal lower wall of said passage being beveled at the ends thereof toward the inclined sides, metal clamps arranged side by side within the passage and having their opposite ends enlarged and rounded to engage 110 within the side walls provided by the passage, the lower portions of the bodies of each of the clamp members being horizontally straight, the upper walls being rounded to their inner walls and their inner walls being beveled to their ends and adapted to be arranged horizontally straight when the said members rest upon the inclined ends of the horizontal lower wall of the passage, and the said members being formed with hooks 115 which are adapted to engage with the longitudinal edges of the rail when the weight of the rail is imposed thereon and the bodies of the members are swung to 120 125

within the tie, and cushion members supporting the rails and disposed to the opposite sides of the rail engaging members.

5. A rail clamp for rails including in combination with a tie, two body members having beveled edges adapted to be received within a recess in the tie, the said members being normally sustained side by side and having their inner edges contacting and 10 adapted to receive the weight of the rail to

swing the same to within the channel and force their outer edges within the side walls provided by the channel, and the said members having rail engaging hooks.

In testimony whereof I affix my signature 15 in presence of two witnesses.

CHARLES HENRY CALHOUN.
